UNITED STATES PATENT OFFICE.

MORGAN EVANS, OF LLANELLY, WALES.

AUTOMATIC LOCKING AND UNLOCKING OF RAILWAY-CARRIAGE DOORS.

1,165,581.

Specification of Letters Patent. Patented Dec. 28, 1915.

Application filed August 9, 1915. Serial No. 44,667.

To all whom it may concern:

Be it known that I, MORGAN EVANS, a subject of His Majesty the King of England, residing at Llanelli, in the county of Carmarthen, Wales, have invented certain new and useful Improvements in the Automatic Locking and Unlocking of Railway-Carriage Doors, of which the following is a specification.

10 This invention relates to improvements in the construction of apparatus for automatically locking and unlocking the doors of railway carriages, said apparatus being controlled by the motion of the carriage and of the heretofore proposed type comprising levers or catches for locking the doors, a dynamo geared to one of the axles of the carriage, and electrically connected to a solenoid or electro-magnet, operative connections between the armature of said solenoid or electro-magnet and the levers or catches and springs or weights to oppose the operation of the solenoid. In such apparatus it has been proposed to pivot the locking levers 25 or catches on the carriage, or to rigidly connect the catches on a longitudinally slidable bar mounted on the side of the carriage and secured to the solenoid armature.

According to the present invention improved means are provided for connecting the solenoid armature to slidable bars to which the locking levers are pivotally connected. Thus, the improved apparatus comprises an electric generator driven from one 35 of the axles of the carriage and electrically connected to a solenoid, a rod secured to the armature of the solenoid, and jointed to a crank or arm on a transverse shaft, weight, spring, or otherwise automatically controlled levers on said shaft, bars mounted to slide longitudinally on the sides of the carriage, door locking levers pivoted on the carriage and jointed to said bars, and bell-crank levers pivoted on the sides of the carriage 45 and jointed to the respective weight or spring controlled levers and the slidable bars.

The invention is hereinafter described with reference to the accompanying drawing 50 which is a partly sectional elevation of a railway coach having the improved apparatus applied thereto.

In carrying out the invention an electric generator O, is mounted underneath the 55 coach, is adapted to be driven from one of the axles P thereof in any suitable manner,

and is electrically connected to a solenoid a also secured under the coach. A rod b secured to the armature of the solenoid is jointed to one end of a crank or arm c, the other end of which is secured or formed on a shaft d mounted to turn axially in bearings fixed underneath the coach. The shaft d extends transversely from side to side of the coach and is fitted at each end with a lever e 65 weighted as shown at f, or provided with any suitable means for automatically controlling the lever. Two bars g are mounted to slide longitudinally on the lower frame of the coach and one on each side of the latter 70 beneath the doors h, and are jointed to the lower ends of locking levers i pivoted on the coach frame at j and having catches k formed at their upper ends for engagement, when the doors are closed, within sockets or 75 the like l provided in said doors. Each of the bars g is jointed to one arm of a bell-crank lever m which is pivoted on the corresponding side of the coach frame at n and has its other arm connected to the respective 80 lever e.

In the drawing the parts of the apparatus are represented in the positions they occupy when the carriage is moving and the doors are locked. These positions are obtained as 85 follows:—When the train starts the electric generator O is driven and energizes the solenoid a, the solenoid attracts its armature and moves the rod b downward (normally the armature is raised out of and above the coil 90 of the solenoid), thus rocking the shaft d and the levers e thereon, the levers rock the bell-crank levers m which slide the bars g longitudinally, and said bars swing the levers i into their locking position, thus 95 fastening all the doors simultaneously. Reversely, as soon as the train comes to a standstill the electric generator O is stopped, the solenoid is thereupon deenergized and releases its armature, which is forced out of 100 the coil automatically, as by the weights, and the parts of the apparatus are moved into their unlocking positions by means of the weights f thus releasing the catches k from all the doors simultaneously. Similarly, in the event of the train being wrecked the locking mechanism releases the levers i 105 from the doors owing to the carriage being brought to a standstill.

If desired, the locking levers i or bell-crank levers m may be detachably jointed to the bars g in any suitable manner to

enable them to be readily disconnected therefrom in the event of accident or for other causes thus allowing one or more of the doors to be opened independently of the 5 electrical apparatus.

The apparatus is foolproof owing to the fact that its action is automatic and dependent upon the motion of the carriage and not upon the vigilance or attention of the 10 driver, guard or other person. Thus all uncertainty of the proper operation of the apparatus is eliminated, and danger and accidents to passengers and property are avoided.

15 What I claim as new and desire to secure by Letters Patent of the United States is:—
Apparatus for automatically locking and

unlocking railway carriage doors, comprising an electric generator driven from one of the axles of the carriage and electrically connected to a solenoid, a rod secured to the armature of said solenoid and jointed to a crank or arm on a transverse shaft, automatically controlled levers on said shaft, bars mounted to slide longitudinally on the sides of the carriage, door locking levers pivoted on the carriage and jointed to said bars, and bell-crank levers pivoted on the sides of the carriage and jointed to the respective automatically controlled levers 30 and slidable bars.

In testimony whereof I have hereunto signed my name to this specification.

MORGAN EVANS.
